UNITED STATES PATENT OFFICE.

WALTER BASTORD, OF MISSION CITY, BRITISH COLUMBIA, CANADA.

LOGGING-HOOK.

1,334,830.

Specification of Letters Patent. Patented Mar. 23, 1920.

Application filed April 17, 1919. Serial No. 290,718.

To all whom it may concern:

Be it known that I, WALTER BASTORD, a subject of the King of Great Britain, and a resident of the town of Mission City, in the Province of British Columbia, Canada, have invented certain new and useful Improvements in Logging-Hooks, of which the following is a specification.

My invention relates to improvements in logging hooks, and the object of my invention is to provide a hook adapted for use in logging operations or other similar work by the use of which the load is securely held to the hauling line, while at the same time 10 connection and disconnection of the load line from the hook is effected with great ease and convenience.

I attain this object by the construction illustrated in the accompanying drawings in 20 which—

Figure 1 is a side view of the hook.

Fig. 2 is an edge view.

Fig. 3 is a fragmentary sectional view showing the locking arrangement.

25 Fig. 4 is a detail view of the locking member.

Similar figures of reference indicate similar parts throughout the several views.

The hook, indicated generally by the 30 numeral 1, is formed as shown in Figs. 1 and 2, having the shank 2 connecting the hook bill 3 with the eyed end 4, on which eyed end is swingably mounted a finger 5 the upper end of which is jawed as at 6 to 35 engage the reduced upper end 7 of the shank, as shown, the finger being held in place by a bolt or pin 8 which passes through the shackle 9, the jaws 6 and the eye 4. The lower end of the finger 5 is provided with a 40 hole 10 in which, when the hook entrance is closed, the point 11 of the hook bill 3 is engaged to prevent side movement of the finger.

12 indicates a rectangular recess formed 45 in one side of the upper end 7 of the shank, through the wall of which recess extends a hole 13, and mounted in the recess for slideable movement therein is a rectangular member 14 having a pin extension 15 adapted to 50 extend slidably through the hole 13. Adjacent the inner end of the member 14 the pin is enlarged to fit the recess, as at 16, the enlarged portion forming a guide for the member 14 to prevent side movement.

55 Mounted on the pin between the wall 17 of the recess and the portion 16 is a spring 18

normally in tension and adapted to be compressed by the act of pressing the member 14 inward, from which it will be seen that the member 14 operates similar to a push 60 button, and as it projects from the side of the hook it may be pushed inwardly at will.

This button 14 extends through a notch 19 in one of the jaws of the finger and on its upper edge it is notched as at 20 and 21, the 65 side face of the notch 20 being normally on the inside of and engaging the finger jaw so that the button cannot be inadvertently displaced while the bottom face of the notch is, when the hook is closed, directly in alignment with the finger notch 19 which then straddles the top edge of the button so that the finger cannot be swung upwardly, as this notch is of less depth than the sides of the finger notch. On pushing the button inwardly, however the notch 21 is brought 70 into alignment with the finger notch 19, and as notch 21 is deeper than the sides of notch 19 the finger may be swung upwardly to open the hook entrance 22, from which 75 it will be seen that to permit swinging the finger up to open the hook all that is necessary is to push in the button 14 the required amount, the closing of the entrance being effected by swinging the finger downwardly 80 until the finger notch 19 registers with the recess 12, when the spring 18 will force the button outwardly so that the notch 19 will engage its top edge and prevent inadvertent 85 unlocking of the finger.

90 From the foregoing it will be seen that I have devised a simple and inexpensive hook which is of great utility and convenience in logging operations.

What I claim as my invention is:

1. In a hook, a finger having its upper end jawed and pivotally connected to the hook head and its free end resting on the hook bill so as to close the hook entrance, one of said jaws having a notch, and a pin mounted 100 in the hook shank having its outer end enlarged and adapted to extend laterally to project through the jaw notch which straddles it to prevent upward movement of the finger, said enlarged end being adapted for 105 inward lateral movement by manual operation so as to carry a notch with which it is provided into alignment with the jaw notch and permit upward movement of the finger.

110 2. In a hook, a finger having its upper end jawed and pivotally connected to the

hook head and its free end resting on the hook bill so as to close the hook entrance, one of said jaws having a notch in its lower edge, and a spring-pressed pin mounted in the hook shank having its outer end enlarged and adapted to extend laterally to project through the jaw notch which straddles it to prevent upward movement of the finger, said enlarged end having a wall 5 which engages the inside of the jaw when the finger is in the closed position to pre-

vent outward movement of the pin and a notch outside the jaw of greater depth than the lower edge of the jaw, the said enlarged end being adapted for inward lateral movement by manual operation so as to carry said notch into alinement with the jaw notch and permit upward movement of the finger. 15

Dated at Vancouver, B. C., this 3rd day of April, 1919.

WALTER BASTORD.
